Fig. 6. 20.

Fig. 3.

A technical line drawing of a mechanical assembly, likely a gear system. It features several circular components with internal holes and various patterns of hatching. The components are labeled with numbers: 24, 23, 45, 33, 11, 15, 17, 13, 12, and 16. The drawing is oriented diagonally, with the top right corner pointing towards the top left.

UNITED STATES PATENT OFFICE.

MARTIN AUGUSTE ROTH, OF LILLE, FRANCE.

MACHINE FOR DRAFTING FIBROUS MATERIALS.

Application filed January 23, 1925, Serial No. 4,355, and in France February 4, 1924.

This invention is for improvements in or relating to machines for drawing or drafting fibrous materials and has for one of its objects to provide a construction which shall be capable of producing satisfactory and economical results even though when dealing with material of comparatively poor quality. Another object of the invention is to provide a mechanism which may be relied upon to give regular and uniform results and which shall be efficient and safe in operation.

According to one feature of the present invention improved means are provided for applying tension to the conveyor band. A long conveyor band is employed and a jockey-pulley relied upon to keep the operative part of the band at the requisite tension, the employment of a long conveyor band being advantageous from many points of view.

According to another feature of the invention there is provided a cleaner for keeping the operative surface of the band free from accumulations of fluff whereby its manipulation of the sliver will be considerably improved more particularly from the point of view of regularity and uniformity. The employment of the cleaner furthermore promotes the satisfactory operation of the remainder of the mechanism since it operates to tend to prevent bearings and other parts from becoming clogged.

The invention also comprises certain features in regard to the guiding and controlling of the jockey-pulley and the cleaner, the protection of the conveyor bands, and the supporting of the various rollers in the feeding and drafting mechanism.

For a more complete understanding of the invention there will now be described, by way of example only and with reference to the accompanying drawings, certain constructional forms of drafting mechanism according to the invention. It is to be understood, however, that the invention is not restricted to the precise constructional details set forth.

In these drawings:—

Figure 1 is an end elevation of a portion of one constructional form of drafting mechanism according to the invention.

Figure 2 is a partial plan view of the mechanism illustrated in Figure 1.

Figure 3 is a perspective view of a detail of the mechanism shown in Figures 1 and 2.

Figure 4 is a more or less diagrammatic

view of a mechanism somewhat similar to that illustrated in Figures 1 and 2.

Figure 5 is a view on the same lines as Figure 4 but showing a modified construction.

Figure 6 is a somewhat similar view of still another construction, and

Figure 7 is a diagrammatic view of another arrangement of the drafting rollers. 65

Figures 8, 9 show a leather covered and milled roller and

Figures 10, 11 show a fluted roller for use in the device as described later.

Like reference numerals indicate like 70 parts throughout the drawings.

Referring firstly to Figures 1, 2 and 3, a portion of the main supporting framework of the machine is shown at 10. In this are supported a lower main sliver feeding 75 roller 11, a lower drafting roller 12, a conveyor band guiding roller 13 and a conveyor band guiding and supporting plate 14. The conveyor band is shown at 15 and it will be seen that it is guided by the rollers 11 and 13. The band 15 may be made of paper, leather, rubber, metal or other convenient material. The entering sliver is illustrated at 16 and the drafted material being delivered is illustrated at 17. Also supported by the frame 10 is a pivoted block 18 in which is mounted a bar 19. This bar 19 serves to support one end of each of the upper main sliver feeding rollers 20, the intermediate feeding and pressure rollers 21, 22 and 23, 80 and the upper drafting roller 24. The ends of the rollers just mentioned are received in blocks such as 25, Figure 3, which are adjustable along the bar 19 and can be secured in position by tightening screws 26. Naturally the dimensions of the blocks 25 will vary according to the dimensions of the rollers they have to support but they are preferably all constructed on substantially 90 the same lines and by virtue of the arrangement just described it will be seen that any desired adjustment of the rollers can readily be obtained. It will usually be necessary to vary the setting of the rollers according to 95 the nature of the material under treatment, or according to the nature of the results desired to be obtained. The other ends of the rollers will be supported by similar blocks on a bar similar to the bar 19 but it has not

been thought necessary to illustrate the complete arrangement since it merely amounts to a duplication of the parts. It will be 100 applied to the other ends of the rollers. 105

110

preciated that any number of slivers may be dealt with side by side along the length of the rollers. Usually it will be preferred to have the rollers 11 and 12 fluted, as shown in Figures 10, 11, or roller 11 may be milled as shown in Figure 9, and the roller 20 plain and the roller 24 covered with leather or similar facing material as shown in Figure 8. The angular setting of the portion of the conveyor band between the rollers 11 and 20 and the rollers 12 and 24 should preferably be in the neighbourhood of 15° to 20° to the horizontal.

Referring now to Figure 4, it will be seen that the conveyor band 15 forms a loop in which is suspended a jockey-pulley 27. This pulley has a spindle 28 which is guided in a fork 29 at the upper end of a portion 30 on the framework of the machine and it will be seen that the jockey-pulley 27 operates solely by reason of its own weight to apply tension to the band 15. As necessary the pulley can rise and fall in the fork 29 in automatically adjusting the tension. The fork 29, in the construction illustrated, also operates to receive the spindle 31 of a cleaning roller 32 which rests against the operative surface of the band 15 and removes therefrom any adhering material such as cotton fluff. The pressure of the roller 32 against the band is entirely automatic and this roller will adjust itself in position to follow any movements of the jockey-pulley in the fork 29.

In the construction shown in Figure 5, the supporting plate 14 underneath the upper portion of the band 15 is not employed. If desired the space between the rollers 11 and 13 may be left entirely free, or alternatively a supplementary supporting roller as indicated in chain lines at 33 may be employed. In this figure, moreover, a modified form of support for the jockey-pulley 27 and cleaning roller 32 is illustrated. The part 30 of the machine frame has at its upper end two fingers 34 and 35 whereof the adjacent faces 36 and 37 respectively converge downwardly. The finger 34 constitutes a guiding abutment against the upwardly extending face 36 of which the jockey-pulley spindle 28 bears, and up and down which face the jockey-pulley is free to move in applying tension to the band. This finger 34 is so situated that its face 36 holds the jockey-pulley, and the loop of the conveyor band in which it is situated, out of the position perpendicularly, though in the same plane, as they would otherwise take up due to gravity. In this respect, of course, the construction shown in Figure 5 operates similarly to that shown in Figure 4, and the result is that the conveyor band and the jockey-pulley are retained under adequate control and prevented from moving into undesired or dangerous positions such as might

result if they were free to swing about. Similarly, the finger 35 constitutes a guiding abutment against the upwardly extending face 37 on which the spindle 31 of the cleaner 32 bears and up and down which it is free to move to adjust itself in rubbing contact with the surface of the band 15. This band, and the face 37, constitute the sole support for the cleaner 32.

In the construction shown in Figure 6, the roller 13 and the plate 14 are substituted by a plate 38 whereof the rounded end 39 serves to guide the band 15 at the point where it is most nearly adjacent to the drafting rollers 12 and 24. In this figure a portion of the frame of the machine is shown at 40 and in addition to supplying the guiding faces 41 and 42 for the jockey-pulley and cleaning roller, this portion 40 is also extended upwardly at 43 to surround and protect the conveyor band 15. Preferably another protecting plate 44 is also provided in the machine frame so that the conveyor bands may be adequately enclosed.

In the arrangement of the rollers shown in Figure 7, a single roller 45 replaces the rollers 21 and 22. It is preferred to have the rollers 11, 12, 23 and 45 fluted in this construction as shown in Figures 10, 11.

The mechanism according to the present invention may be applied to treatment of any fibrous materials and may be adjusted to give any desired degree of draft. It may be applied to machines for imparting a preparatory draft to a sliver or to machines which impart the final draft prior to spinning. Although a high degree of draft may be secured with the mechanism according to the present invention if desired, yet in some circumstances it will be found more satisfactory to secure a lower draft and to rely upon the mechanism to equalize the strength and character of the output with the object of reducing the subsequent number of "doublings" required. Any lengths of fibers may be dealt with and in this respect the invention will be found to be particularly applicable for dealing with material having mixed long and short fibers since, owing to the high degree of efficiency with which the conveyor band operates, the long and short fibers will be adequately distributed and the resulting drafted yarn be found to be regular and uniform in strength and texture with the various fibers laid regularly and straight, no matter whether these fibers were originally on the outside edges or in the middle of the band of sliver.

The weights, speeds, and operative pressure of the feeding, intermediate and drafting rollers, upon the material under treatment may be varied and adjusted as desired and if thought necessary spring tension means may be applied to the bars 19. The conveyor band can be arranged to sup-

port the material during practically the whole of its travel from the intake of the main feeding rollers to the intake of the drafting rollers and in this way adequate control may be secured over the material. This control may be further adjusted by choosing a suitable spacing for the various rollers along the bars 19.

Friction may be relied upon solely for driving the band 15 or alternatively the roller 11 could be fitted with a toothed wheel to engage in perforations in an edge of the band. The cleaning roller 32 may be provided with a suitable operative face of cloth or other convenient material.

It is to be understood that the invention is not restricted to the precise constructional details hereinbefore set forth.

I claim:-

20 1. A machine for drawing or drafting fibrous materials comprising in combination a drafting device, a feeding and restraining device co-operating therewith, an endless conveyor band for the fibrous material being treated, means for driving and guiding said band in such a path that a portion of its periphery affords a guiding and conveying surface for substantially the whole length of the fibrous material between its intake at the feeding and restraining device and the drafting device, the length of which band is such that the portion of its periphery which forms the conveying surface is considerably less than one-third of the length of the entire band and that the remainder of the band depends in the form of a straight-sided loop the bight of which occurs at a situation considerably remote from the drafting locality, a jockey pulley freely suspended in said loop and a stationary abutment by which the jockey pulley is guided for rising and falling movement.

2. A machine for drawing or drafting fibrous materials comprising in combination a drafting device, a feeding and restraining device co-operating therewith, an endless conveyor band for the fibrous material being treated, means for driving and guiding said band in such a path that a portion of its periphery affords a guiding and conveying surface for substantially the whole length of the fibrous material between its intake at the feeding and restraining device and the drafting device, the length of which band is such that the portion of its periphery which forms the conveying surface is considerably less than one-third of the length of the entire band and that the remainder of the band depends in the form of a straight-sided loop the bight of which occurs at a situation considerably remote from the drafting locality, a jockey pulley freely suspended in said loop, a rotary cleaner bearing against and driven by that surface of the band which engages the

fibrous material and a stationary abutment arranged to maintain both the jockey pulley and the rotary cleaner in operative position against the band.

3. A machine for drawing or drafting 70 fibrous materials comprising in combination a drafting device, a feeding and restraining device co-operating therewith, an endless conveyor band for the fibrous material being treated, means for driving and guiding said band in such a path that a portion of its periphery affords a guiding and conveying surface for substantially the whole length of the fibrous material between its intake at the feeding and restraining device and the drafting device, said band being long enough to form a depending loop which hangs below the aforesaid portion of its periphery, a jockey pulley suspended in said depending loop and operating by reason solely of its own weight to apply tension to the band, and a guiding abutment having an upwardly extending face against which the jockey pulley bears, and up and down which the jockey pulley is free to move in applying tension to the band, said abutment being so situated as to hold the jockey pulley, and the loop of the band in which it is situated, out of the position perpendicularly though in the same plane as they would otherwise take up due to gravity.

4. A machine for drawing or drafting fibrous materials comprising in combination a drafting device, a feeding and restraining device co-operating therewith, an endless conveyor band for the fibrous material being treated, means for driving and guiding said band in such a path that a portion of its periphery affords a guiding and conveying surface for substantially the whole length of the fibrous material between its intake at the feeding and restraining device and the drafting device, said band being long enough to form a depending loop which hangs below the aforesaid portion of its periphery, a jockey pulley suspended in said depending loop and operating by reason solely of its own weight to apply tension to the band, a cleaner bearing upon that surface of the band which engages the fibrous material being treated, and a guiding abutment having an upwardly extending face against which the cleaner bears and up and down which it is free to move to adjust itself in rubbing contact with the surface of the band, the latter and the face of the abutment constituting the sole support for the cleaner.

5. A machine for drawing or drafting fibrous materials comprising in combination a drafting device, a feeding and restraining device co-operating therewith, an endless conveyor band for the fibrous material being treated, means for driving and guiding said band in such a path that a portion of its periphery affords a guiding and convey-

- ing surface for substantially the whole length of the fibrous material between its intake at the feeding and restraining device and the drafting device, said band being 5 long enough to form a depending loop which hangs below the aforesaid portion of its periphery, a jockey pulley suspended in said depending loop and operating by reason solely of its own weight to apply tension to 10 the band, a cleaner bearing upon that surface of the band which engages the fibrous material being treated, and two guiding abutments, one having an upwardly extending face against which the jockey pulley 15 bears, and up and down which the jockey pulley is free to move in applying tension to the band, said abutment being so situated as to hold the jockey pulley, and the loop of the band in which it is situated, out of the 20 position perpendicularly though in the same plane as they would otherwise take up due to gravity, and the other guiding abutment having an upwardly extending face against which the cleaner bears and up and down 25 which it is free to move to adjust itself in rubbing contact with the surface of the band, the latter and the face of the said second abutment constituting the sole support for the cleaner.
- 30 6. A machine for drawing and drafting fibrous materials comprising in combination a drafting device, a feeding and restraining device co-operating therewith, an endless conveyor band for the fibrous material being treated, means for driving and guiding said band in such a path that a portion of its periphery affords a guiding and conveying surface for substantially the whole length of the fibrous material between its intake at 35 the feeding and restraining device and the drafting device, said band being long enough to form a depending loop which hangs below the aforesaid portion of its periphery, a jockey pulley suspended in said depending 40 loop and operating by reason solely of its own weight to apply tension to the band, a cleaner bearing upon that surface of the band which engages the fibrous material being treated, and a guiding member having 45 two upwardly extending opposed converging faces, against one of which faces the jockey pulley bears, and up and down which the 50
- jockey pulley is free to move in applying tension to the band, such face being so situated as to hold the jockey pulley, and the loop of the band in which it is situated, out of the 55 position perpendicularly though in the same plane as they would otherwise take up due to gravity, and the other of said faces having the cleaner bearing against it and being free 60 to move up and down it to adjust itself in rubbing contact with the surface of the band, the latter and the said second face constituting the sole support for the cleaner.
7. A machine for drawing or drafting fibrous materials comprising in combination two parallel bars, a plurality of pairs of blocks slidably carried by said bars, each pair having one block on one bar and the second on the other bar, a set of constantly 70 rotating drafting rollers, a set of feeding rollers associated with said drafting rollers, a plurality of intermediate rollers carried each by one of said pairs of blocks between said feeding and drafting rollers, which 75 blocks are adjustable along said bars each independently of the others, the foremost one of the said intermediate rollers being adjustable into close proximity with the drafting rollers to reduce to a minimum the distance between the foremost intermediate 80 roller and the nip of the drafting rollers, an endless conveyor band for the fibrous material being treated, means for driving and guiding said band in such a path that a portion of its periphery affords a guiding and conveying surface at said intermediate rollers for substantially the whole length of the fibrous material between its intake at the 85 feeding rollers and the drafting rollers, the length of which band is such that the portion of its periphery which forms the conveying surface is considerably less than one-third of the length of the entire band and that the remainder of the band depends in 90 the form of a straight-sided loop the bight of which occurs at a situation considerably remote from the drafting locality, a jockey pulley freely suspended in said loop and a stationary abutment by which the jockey pulley is guided for rising and falling movement.
- 95 In testimony whereof I affix my signature.
MARTIN AUGUSTE ROTH.
